CLAIM

The ornamental design for a cap as shown and described.

DESCRIPTION

FIG. 1 is a top rear side perspective view of a cap showing my new design;
FIG. 2 is a top front side perspective view of the cap;
FIG. 3 is a front view of the cap;
FIG. 4 is a rear view of the cap;
FIG. 5 is a left side view of the cap;
FIG. 6 is a right side view of the cap;
FIG. 7 is a top view of the cap;
FIG. 8 is a bottom view of the cap; and,
FIG. 9 is a top rear side perspective view of the cap in use. The broken lines on the cap are illustrative of stitching forming no part of the claimed design. The broken lines in FIG. 9 extrinsic to the cap are illustrative of environmental structure forming no part of the claimed design.
